ABSTRACT

An improvement in capsule making apparatus is provided in the form of air duct means for conditioning freshly dipped capsule mold pins at a point in the work cycle just prior to the elevation of the pin bars to the drier stage. The film coating on the pins is thereby stabilized so that asymmetric film flow during transfer and elevation is substantially decreased.

CAPSULE MAKING APPARATUS

SUMMARY AND DETAILED DESCRIPTION:

This invention relates to capsule making apparatus and more particularly to an improvement in means for cooling freshly dipped capsule pins to provide for better film-forming characteristics.

Production of hard shell pharmaceutical capsules by conventional means involves a series of steps in which bar-mounted capsule mold pins are first dipped in liquid gel solution and the bars holding the pins coated with fresh liquid film are then transferred to an elevator and elevated with rotation to an upper drying rack for movement through drying kilns until the film has solidified. It has been considered essential in this operation to rotate the pin bars during elevation in order to maintain uniform distribution of the liquid film on the pins. Nevertheless, the practice often results in a non-uniform thickness in the capsule shell wall, particularly in the so-called shoulder area. It is found, for example, that the shoulder wall on the leading side of the pin in the direction of the rotation is usually thin whereas on the trailing side it is relatively thick.

It is therefore an object of the present invention to provide improved means for handling freshly dipped capsule mold pins.

It is also an object of the invention to provide economical means for making capsules having improved wall thickness characteristics.

It is a further object of the invention to provide means for maintaining a balanced radial distribution of film in the production of dip-molded capsules, particularly in the shoulder area.

These and other objects, features and purposes of the invention will be seen from the following description in relation to the accompanying drawing in which:

FIG. 1 is an elevational view partly in section of capsule making apparatus including a dipping tank, elevator and air duct system;

FIG. 2 is a view of the air duct of FIG. 1;

FIG. 3 is a fragmented view of an air duct; and

FIGS. 4 and 5 are enlarged views of coated mold pins in the pin down and pin up positions, respectively.

Referring to FIG. 1, the dipping tank 10 which may be conventional in form includes a dipping dish 11 surrounded by a reservoir 12 containing dipping solution 13 in a constant temperature jacket 14. Capsule pins 20 mounted on bars 21 are located, as illustrated, at successive work stations of the operation: at the dipping station A, at the base or loading station B of an elevator 30, at the unloading station C (dotted outline), and at a platform 40 which is the starting run D through a series of driers. Mechanical finger means (not shown) are provided in connection with each dipping cycle for engaging and sliding the pin bar set at A along a guide track 22 into the loading station B of the elevator. The elevator has a pair of vertical racks 31 which cooperate with a like pair of pinion gears 32 and discs 33. The two discs each have a groove 34 and are spaced in the loading position illustrated, with the grooves in alignment with the top surface of the guide track 22, to receive the opposite ends of each advancing pin bar for loading. Surrounding the elevator disc 33 is a flanged retainer ring 35 which remains stationary with respect to the disc and thus serves to retain the pin bars within the groove as the disc rotates while moving upwardly on the rack. The gear and rack combination is arranged

for movement of the elevator to the upper terminal position C illustrated in dotted outline at which the elevated pin bars stand in the pin up position for transfer from the groove 34 to the platform 40. In accordance with a preferred embodiment of the invention shown in FIGS. 1 and 2, an air duct or conduit 50 is provided having an open outlet 51 located below the loading position B. The air duct communicates with a suitable source (not shown) of clean air under positive pressure at room temperature or lower temperature. As shown, the air duct outlet 51 is sufficiently large to surround the array of pin ends 20a of bars at the loading station. In this regard, the end of the conduit 50 may have an outward flare 52 to favor a greater outward flow of air around the perimeter of the array of pins.

The embodiment shown in FIG. 2 features distribution baffles 53 and a screen tray 54 which insure uniform air flow across the opening 51 through the confined zone surrounding the pin ends 20a at the loading station. The screen tray preferably fits the outlet opening closely and is removable for cleaning purposes.

In another preferred embodiment illustrated in FIG. 3 the air duct 50a is located directly above the loading station B. It constitutes a suction chamber which surrounds the elevator and communicates with a suitable source of suction, preferably remote from the elevator, which serves to exhaust air through the duct by way of the intake openings 51a and 51b. Opening 51a which is rectilinear and extends around each array of pins standing at the loading position B provides for intake of atmospheric air through the confined zone surrounding the ends of pins so located. Opening 51b serves to provide clearance for unloading the bars 21 from station C to the platform 40.

OPERATION

In a typical operation, the pins 20 are dipped in gel solution, withdrawn, exposed to air flow and transferred to the loading station B, elevated with rotation, transferred to the drier, dried, stripped, and greased (in preparation for the next cycle). For dipping, the solution which may be an aqueous gelatin solution is maintained at a suitable temperature, conveniently in the range from about 110°-115° F. The pins are dipped five bars at a time at the rate of 20 bars per minute. The time required for dipping, loading, and elevation and transfer to the drying platform 40 is about 15 seconds. Transfer to the elevator (position A to position B) requires less than one second, following which the pin bar sets come to a dead stop. In accordance with the invention, air is delivered through the orifice 51 (or 51a, FIG. 3) under conditions such as to cool and stabilize the film coating on the pins, for example at room temperature or lower under controlled humidity, preferably 50 percent or lower, and at a linear flow rate of about 5 feet per second. The air-flow conveniently is continuous so that the pins are exposed to the same during the transfer to position B and during the dead stop and elevation. Substantially all of the film-stabilizing effect takes place during the transfer and dead stop. Thereafter the elevator is activated in conventional manner and the loaded pin bar sets are rotated to the terminal position C adjacent the drier platform 40. While being elevated the pins are rotated (standard rotation is two and one-half times) from the pin down position to the pin up position illustrated in dotted outline. Following a short dwell time, the pin

sets are transferred to the drier platform 40 and are then processed through the remainder of the cycle in conventional fashion.

In the described loading and elevation by conventional means the individual pins undergo linear and radial acceleration which it is found deforms the wet film coating. FIG. 4 illustrates the deformation of the film coating 22a shown in dotted outline as the pin 20 is being rotated from the load position and elevated. By comparison, according to the present invention, the film coating 22b shown in solid outline is typical of the air treated coating during the same phase of rotation. Advantageously, the film coating at the shoulder line 20b remains substantially uniform. Similarly, FIG. 5 illustrates the configuration of the coating of the fully elevated pin. The dotted outline 22b illustrates the coating profile as the pin first arrives at position C. The solid outline 22c illustrates the profile of the finished film dried on the pin. Thus, prior to the drying step the film coating at the end 20a of the pin is relatively thick. However, with progressive drying the coating evenly redistributes itself axially upon the surface of the pin to provide a generally uniform thickness.

A critical measure of quality of molded capsules concerns the variation in wall thickness at the shoulder line 20b. Ideally, the wall thickness in a given capsule should be constant throughout the shoulder line. Also, the wall should be relatively thick at the shoulder. To illustrate the advantage obtained by the present invention in this respect, the following tables provide a comparison of values for minimum and maximum wall thickness at the shoulder line in capsules produced according to the present invention and control capsules produced by conventional means.

TABLE I
Capsule Wall Thickness at Shoulder (MIN.)

Capsules Produced with Pre-elevation		Control Capsules	
Cooling Means Frequency Percent	Thickness (mils)	Frequency Percent	Thickness (mils)
4	3.8	12	2.8
12	3.9	20	2.9
28	4.0	8	3.0
24	4.1	8	3.1
12	4.2	16	3.2
4	4.3	8	3.3
8	4.4	12	3.4
4	4.5	4	3.5
4	4.8	8	3.6
		4	3.8
Average,	4.15 mils	Average,	3.19 mils
Standard deviation,	0.22	Standard deviation,	0.28

TABLE II
Capsule Wall Thickness at Shoulder (MAX.)

4	4.4	5	4.1
8	4.5	11.8	4.3
20	4.6	11.8	4.4
8	4.7	7.8	4.5

8	4.8	23.5	4.6
12	5.1	15.7	4.7
12	5.2	5	4.8
8	5.3	7.8	5.0
8	5.4	3.9	5.4
8	5.5	3.9	5.5
5	5.7	3.9	5.7
Average, 4.99 mils		Average, 4.60 mils	
Standard deviation, 0.38		Standard deviation, 0.38	

These results show that the capsules produced according to the present invention with respect to shoulder wall were superior to control capsules both as to thickness and variation in thickness.

While the invention in capsule making apparatus has been described in the foregoing description in considerable detail, it will be realized by those skilled in the art that wide variation of such detail can be made without departing from the scope of the present invention as claimed in the following claims.

We claim:

1. In capsule making apparatus comprising a set of capsule pin bars having elongated pins each pin having a rounded end, a dipping tank, and means for transferring the pin bars continuously in timed relation through a stepwise cycle of pin dipping in gel solution, withdrawing and inverting the pins while coated with liquid film which is subject to uneven distribution during transfer under action of gravity, and drying and stripping the coating on the pins, the transfer means including an elevator for lifting and rotating pin bars from a loading station and means for supplying the loading station with bars of freshly dipped pins with the rounded end of each pin lowermost,

the improvement characterized by air conduit means having a distribution orifice located adjacent the loading station for moving cooling air upwardly against the rounded ends of the coated pins, the orifice being shaped to provide for uniform flow through a confined zone surrounding the array of pin ends of bars at the loading station.

2. Apparatus according to claim 1 where the distribution orifice is located below the loading station and the air conduit means is in communication with a source of positive air pressure.

3. Apparatus according to claim 1 wherein the distribution orifice is located above the loading station and the air conduit means is in communication with a source of negative air pressure.

4. Apparatus according to claim 1 wherein the air conduit means is in communication with a source of air pressure adapted to generate air flow through the confined zone at a rate sufficient to stabilize the liquid film coating on coated pins located at the loading station.

5. Apparatus according to claim 3 wherein the air conduit means comprises a chamber surrounding the elevator.
